CLAIM

The ornamental design for a hinged grill lid, as shown and described.

DESCRIPTION

FIG. 1 is a front, left perspective view of a first embodiment of my new design for a hinged grill lid shown in a grilling environment;

FIG. 2 is a top plan view of the hinged grill lid shown in FIG. 1 removed from the grilling environment;

FIG. 3 is a bottom plan view thereof;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a front, left perspective view of another embodiment of my new design for a hinged grill lid;

FIG. 9 is a top plan view thereof;

FIG. 10 is a bottom plan view thereof;

FIG. 11 is a front elevation view thereof;

FIG. 12 is a rear elevation view thereof;

FIG. 13 is a right side elevation view thereof; and,

FIG. 14 is a left side elevation view thereof.

The broken lines in the drawings depict environmental subject matter only and form no part of the claimed design.
